HEAD REGISTRATION ADJUSTING MECHANISM FOR DUPLICATORS

John L. Tregay, Broadview, Ill., assignor to A. B. Dick Company, Niles, Ill., a corporation of Illinois

Application September 19, 1956, Serial No. 610,744

7 Claims. (Cl. 101—248)

This invention relates to printing machines or duplicators and pertains particularly to a mechanism for adjusting the head registration. By head registration is meant the position of the printed matter with respect to the head of the sheet printed on the duplicator.

Thus, one principal object of the present invention is to provide a new and improved head registration adjusting mechanism for duplicators.

A further object is to provide a new and improved head registration adjusting mechanism which is applicable to all types of duplicators but is especially advantageous when used in connection with a three-cylinder offset printing machine utilizing the lithographic process.

Another object is to provide a new and improved head registration adjusting mechanism whereby the positions of the blanket and master cylinders of a three-cylinder machine may be changed relative to the position of the impression cylinder, without changing the relative positions of the blanket and master cylinders.

A further object is to provide a new and improved head registration adjusting mechanism whereby the blanket cylinder is readily and positively located in the position for effecting the adjustment and is maintained stationary in this position while the adjustment is being made.

It is a further object to provide such a new and improved head registration adjusting mechanism in which a slidable and rotatable wrench is adapted to extend through a locating aperture in a positioning member on the blanket cylinder, so as to align the wrench with a rotatable adjusting member, while maintaining the blanket cylinder stationary.

Another object is to provide a new and improved adjusting mechanism which greatly facilitates the head registration adjustment.

A further object is to provide a new and improved head registration adjusting mechanism which is effective and convenient in operation, yet is relatively simple and low in cost.

Further objects and advantages of the present invention will appear from the following description, taken with the accompanying drawings, in which:

Fig. 1 is a diagrammatic side view of a lithographic offset printing machine or duplicator equipped with a head registration adjusting mechanism which constitutes an illustrative embodiment of the present invention.

Fig. 2 is an elevational view, partly in section, generally along a line 2—2 in Fig. 1, showing the offset cylinder of the three-cylinder printing machine.

Fig. 3 is a diagrammatic sectional view, taken generally along a line 3—3 in Fig. 2, and showing the gears which connect the three cylinders of the printing machine.

Fig. 4 is a fragmentary enlarged sectional view taken generally along a line 4—4 in Fig. 2.

Fig. 5 is a sectional view taken generally along a line 5—5 in Fig. 2.

Fig. 6 is an enlarged elevational view of the indicia

carried by the gears on the blanket cylinder, the same indicia being shown on a smaller scale in Fig. 2.

As already indicated, the drawings illustrate a three-cylinder printing machine or duplicator 10 (Fig. 1), which 5 may be of the lithographic offset type. However, it will be understood that the present invention is also applicable to duplicators of other types and having any suitable number of cylinders.

The offset duplicator 10 of Fig. 1 is equipped with an 10 offset or a blanket cylinder 12 which is engageable with a master cylinder 14 and an impression cylinder 16. It will be understood that the master cylinder 14 is adapted to hold a master sheet or plate on which an ink image 15 of the printed matter or the like is formed. The ink image is transferred to a blanket 18, wrapped around the blanket cylinder 12. From the blanket 18, the image is again transferred to a sheet of paper fed between the blanket and impression cylinders 12 and 16. The blanket 18 may be made of rubber or other suitable composition.

The cylinders 12, 14 and 16 are rotatable and are 20 adapted to be driven in unison by gearing or the like now to be described. In the illustrated embodiment, a gear 20 is secured to one end of the blanket cylinder 12 25 and is arranged to mesh with a gear 22 fixed on one end of the master cylinder 14. The blanket cylinder 12 also carries a ring gear 24 which is adjustable in angular position relative to the gear 20. The adjustable ring gear 24 meshes with a gear 26 secured to the impression cylinder 16. A suitable motor, not shown, may be arranged 30 to drive any of the three cylinders, usually the blanket cylinder 12. In the illustrated machine, the cylinders may be rotated manually by turning a hand wheel 28 mounted on a shaft 30 which carries a pinion 32, meshing with 35 the ring gear 24.

The adjustable ring gear 24 may be mounted on the 40 blanket cylinder 12 in various ways. In the illustrated case, the ring gear 24 is slidably received around a reduced, cylindrical end portion 31 (Fig. 5) on the gear 20. It will be seen that the ring gear 24 has a cylindrical 45 inner surface 33 which fits around the reduced portion 31. The first gear 20 is also ring-shaped in form and is arranged to fit closely over a reduced portion 34 on the blanket cylinder 12. The gears 20 and 24 have flat 50 interengageable end faces 36 and 38. Cylindrical surfaces 40 and 42 are formed on the gears 20 and 24 adjacent the end faces 36 and 38. Indicia may be inscribed on the surfaces 40 and 42 to indicate the relative angular positions of the gears 20 and 24. In this case, the indicia include an index mark 44 on the gear 20 and a scale 46 on the gear 24.

The ring gear 24 is adapted to be held against the gear 20 by a ring-shaped clamping plate 48 which is engageable with an end face or shoulder 52 formed on the outer 55 end of the ring gear. It will be seen that the clamping plate 48 fits around the reduced portion 34 on the cylinder 12.

The clamping plate 48 is adapted to be clamped against the ring gear 24, by means now to be described. When the ring gear is thus clamped, it is held against the gear 20 and thus is immovable with respect to the blanket cylinder. Accordingly, the gear 24 rotates with the blanket cylinder and completes the driving connection between the impression cylinder 16 and the blanket cylinder 12.

In the illustrated construction, the plate 48 is adapted 60 to be clamped against the ring gear 24 by a pull rod 54 having a reduced, threaded end portion 56 which extends through the plate 48. A nut 58 is screwed on to the end portion 56 and securely tightened to hold the rod 54 in fixed relation to the plate 48. The pull rod 54 is slidable in an opening 60 formed in the gear 20, and

in a series of aligned, longitudinal bores 62, 64, 66 and 68 formed in the blanket cylinder 12. It will be seen that the rod 54 extends lengthwise entirely through the blanket cylinder 12. Thus, the bore 68 extends through an end wall 70 at the opposite end of the cylinder from the adjustable ring gear 24. The rod 54 extends through the bore 68 and has an externally threaded end portion 72 projecting beyond the end wall 70. A rotatable clamping member in the form of a nut 74 is screwed onto the end portion 72. Thus, the gear 24 is clamped and unclamped by tightening and loosening the nut 74.

The nut 74 is adapted to be operated by a special wrench 76. To position the blanket cylinder 12 so that the nut 74 will be aligned with the wrench 76, the cylinder 12 is provided with a positioning plate or disk 78 which is secured to the end of the cylinder 12 and is spaced outwardly from the nut 74. A locating hole or opening 80 is formed in the positioning plate 78 opposite the nut 74.

By means now to be described, the wrench 76 may be moved against the positioning plate 78 and through the locating hole 80, so as to engage the nut 74. It will be seen that the nut 74 and the wrench 76 are provided with complementary formations which are adapted to interlock so as to transmit torque from the wrench to the nut. In the illustrated construction, the nut has a pair of radial lugs or blades 82 projecting from the outer end thereof, while the wrench 76 is formed with a kerf or slot 84 adapted to receive the lugs 82. The wrench 76 has a cylindrical outer surface 86 to fit through the locating hole 80.

It will be seen that the wrench 76 is fixed on one end of a shaft 88 which is rotatable and slidable in a fixed guide 90. A handle or hand wheel 92 is mounted on the other end of the shaft. By pushing the handle 92 inwardly, the wrench 76 may be advanced against the positioning plate 78. A spring 94 is arranged between the guide 90 and the shaft 88 so that the wrench 76 will normally be biased away from the positioning plate 78.

The limits of the relative movement between the gear 24 and the gear 20 are defined by pins 96 and 98 which extend outwardly from the outer face of the clamping plate 48 and are engageable by a radial arm 110, rotatable with the ring gear 24. In this case, the outer end of the arm 110 fits into a notch or slot 102 defined between bosses or lugs 104 and 106 on the outer end of the adjustable ring gear 24. The arm 110 may be employed to drive various cams or the like, not shown.

When it is desired to make the registration adjustment, the handle 92 is pushed inwardly to advance the wrench 76 against the positioning plate 78. Next, the hand wheel 28 is rotated so as to turn the blanket cylinder 12 until the locating hole 80 comes into alignment with the wrench 76. Pressure is maintained on the handle 92 so that the wrench 76 will immediately enter the locating hole 80. The wrench 76 thereby locks the blanket cylinder 12 against rotation. By turning the handle 92, the kerf 84 on the wrench may be engaged with the lugs 82 on the nut 74. Then, the handle 92 may be turned to loosen the clamping nut 74. This relaxes the tension on the rod 54 and relieves the clamping pressure on the ring gear 24. The hand wheel 28 is then rotated to turn the ring gear 24 and the impression cylinder 16 to the desired position, as indicated by the indicia 44 and 46. The blanket cylinder 12 and the master cylinder 14 remain stationary due to the locking action of the wrench 76 and the positioning plate 78. The movement of the impression cylinder 16 with respect to the blanket and the master cylinders 12 and 14 changes the head registration. When the desired adjustment has been achieved, the handle 92 is rotated so as to tighten the nut 74 and thereby clamp the gear 24 to the blanket cylinder 12. The handle 92 is then released, whereupon the spring 94 retracts the wrench 76 out of engagement with the nut 74 and the positioning plate 78.

Since the relative positions of the blanket and master cylinders 12 and 14 are not changed, the image is transferred from the master to the blanket cylinder as before, and there is no need to clean the blanket 18 on the cylinder 12.

It will be appreciated that the head registration adjustment may be made very quickly and easily. Moreover, the adjustment may be made with great accuracy by referring to the indicia on the gears 20 and 24.

Various modifications, alternative constructions, and equivalents may be employed without departing from the true spirit and scope of the present invention, as exemplified in the foregoing description and defined in the following claims.

I claim:

1. In a printing machine, the combination comprising a master cylinder, an offset cylinder engageable with said master cylinder, an impression cylinder engageable with said offset cylinder, a first gear secured to one end of said offset cylinder, a second gear meshing with said first gear and secured to said master cylinder, a third gear mounted on said offset cylinder adjacent said first gear for angular adjustment relative to said offset cylinder, a fourth gear meshing with said third gear and secured to said impression cylinder, a clamping plate engageable with said third gear for disengageably clamping said third gear against said first gear, indicia on said first and third gears to indicate the relative angular positions thereof, a rod secured to said clamping plate and extending longitudinally through said offset cylinder, said rod having a threaded end portion extending outwardly beyond the opposite end of said offset cylinder, a nut screwed onto said threaded end portion for tensioning said rod and thereby clamping said third gear, a positioning plate secured to said opposite end of said offset cylinder and having a locating hole therein positioned opposite said nut, a wrench movable against said positioning plate and through said hole into engagement with said nut, said wrench and said nut having complementary formations adapted to interlock for transmitting torque between said wrench and said nut, a shaft supporting said wrench and having handle means thereon, means supporting said shaft for rotation and sliding movement toward and away from said positioning plate, and spring means biasing said shaft away from said positioning plate.
2. In a registration adjusting mechanism for a printing machine, the combination comprising a rotatable printing cylinder, a gear mounted thereon for angular adjustment relative thereto, an operating member mounted on said cylinder for rotation relative thereto, means on said cylinder and operable by said member in response to rotation thereof for disengageably locking said gear to said cylinder, a positioning plate secured to said cylinder and having a locating hole therein opposite said operating member, a wrench mounted adjacent said cylinder for rotation and translatory movement against said plate and through said hole into engagement with said operating member, the reception of said wrench in said hole being effective to locate said cylinder in a stationary position with said operating member aligned with said wrench, said wrench and said operating member having complementary interengageable formations thereon for transmitting torque between said wrench and said operating member, and means biasing said wrench away from said plate.
3. In a registration adjusting mechanism for a printing machine, the combination comprising a rotatable printing cylinder, a gear mounted thereon for angular adjustment relative thereto, an operating member mounted on said cylinder for rotation relative thereto, means on said cylinder and operable by said member in response to rotation thereof for disengageably securing said gear to said cylinder, positioning wall means on said cylinder and having a locating opening therein opposite said operating member, and a wrench mounted adjacent said cylinder for rotation and translatory movement against said wall

means and through said opening into engagement with said rotatable member, the reception of said wrench in said opening being effective to locate said cylinder in a stationary position with said operating member aligned with said wrench, said wrench and said operating member having complementary interengageable formations thereon for transmitting torque between said wrench and said operating member.

4. In a registration adjusting mechanism for a printing machine, the combination comprising a rotatable printing cylinder, a gear mounted thereon for angular adjustment relative thereto, a screw member mounted on said cylinder for rotation relative thereto, means on said cylinder and operable by said member in response to rotation thereof for disengageably clamping said gear to said cylinder, a positioning plate secured to said cylinder and having a locating opening therein opposite said rotatable screw member, a wrench mounted for rotation and translatory movement against said plate and through said opening into engagement with said rotatable screw member, the reception of said wrench in said opening being effective to locate said cylinder in a stationary position with said screw member aligned with said wrench, said wrench and said rotatable member having complementary interengageable formations thereon for transmitting torque between said wrench and said rotatable member, and spring means biasing said wrench away from said plate.

5. In a printing machine, the combination comprising a printing cylinder, a gear mounted on said cylinder for angular adjustment relative thereto, a clamping plate engageable with said gear for disengageably clamping said gear to said cylinder, a rod secured to said clamping plate and extending longitudinally through said cylinder, said rod having a threaded end portion extending outwardly beyond the opposite end of said cylinder, a nut screwed onto said threaded end portion and engageable with said cylinder for tensioning said rod and thereby clamping said gear, a positioning plate secured to said opposite end of said cylinder and having a locating opening therein positioned opposite said nut, a wrench movable against said positioning plate and through said opening into engagement with said nut, said wrench and said nut having complementary formations adapted to interlock for transmitting torque between said wrench and said nut, a shaft supporting said wrench and having handle means thereon, means supporting said shaft for rotation and translatory movement toward and away from said positioning plate, and spring means biasing said shaft away from said positioning plate.

6. In a printing machine, the combination comprising a printing cylinder, a first gear secured to one end of said cylinder, a second gear mounted on said cylinder adjacent said first gear for angular adjustment relative to said cylinder, a clamping plate engageable with said second gear for disengageably clamping said second gear against said first gear, indicia on said gears to indicate

the relative angular positions thereof, a rod secured to said clamping plate and extending longitudinally through said cylinder, said rod having a threaded end portion extending outwardly beyond the opposite end of said cylinder, a nut screwed onto said threaded end portion for tensioning said rod and thereby clamping said second gear, a positioning plate secured to said opposite end of said cylinder and having a locating opening therein positioned opposite said nut, a wrench movable against said positioning plate and through said opening into engagement with said nut, said wrench and said nut having complementary formations adapted to interlock for transmitting torque between said wrench and said nut, a shaft supporting said wrench and having handle means thereon, means supporting said shaft for rotation and sliding movement toward and away from said positioning plate, and spring means biasing said shaft away from said positioning plate.

7. In a printing machine, the combination comprising a master cylinder, an offset cylinder engageable with said master cylinder, an impression cylinder engageable with said offset cylinder, a first gear secured to one end of said offset cylinder, a second gear meshing with said first gear and secured to said master cylinder, a third gear mounted on said offset cylinder for angular adjustment relative to said offset cylinder, a fourth gear meshing with said third gear and secured to said impression cylinder, an operating member mounted on said offset cylinder for rotation relative thereto, means on said offset cylinder and operable by said member in response to rotation thereof for disengageably securing said third gear to said offset cylinder, positioning wall means on said offset cylinder and having a locating opening therein positioned opposite said operating member, and a rotatable wrench mounted adjacent said offset cylinder for translatory movement against said positioning wall means and through said opening into engagement with said operating member, the reception of said wrench in said opening being effective to locate said offset cylinder in a stationary position with said operating member aligned with said wrench, said wrench and said operating member having complementary formations adapted to interlock for transmitting torque between said wrench and said nut.
